MAGAZINE COVER-REMOVING MACHINE

William J. Havely, Los Angeles, Calif., assignor to
Mekana Strip Company, Inc., Arcadia, Calif.,
a corporation of California

Application December 4, 1948, Serial No. 63,471

8 Claims. (Cl. 164—61)

1

This invention relates to a machine for removing the covers of magazines and is an improvement of the machine disclosed in my pending application, Serial No. 11,495, filed February 27, 1948 which has become abandoned.

An object of the present invention is to provide an automatic machine that conveys successive magazines from a stack past means that raises, opens and finally severs the covers of the magazines before depositing the coverless magazines in overlapping relation for ready removal.

Another object of the invention is to provide a machine of the character indicated that embodies novel adjustable means controlling the feed of the magazines according to the thickness thereof.

Another object of the invention is to provide improved cover-lifting means that is adapted to be adjustably positioned according to the width of the magazines handled by the machine.

A further object of the invention is to provide, in a machine of the character indicated, means for feeding magazines from the bottom of a stack thereof, whereby a continuous uninterrupted operation is obtained since the stack can be replenished during operation.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views:

Fig. 1 is a top plan view of a machine according to the present invention, the means receiving the coverless magazines being broken away.

Fig. 2 is a front elevational view thereof.

Figs. 3 and 4 are enlarged vertical sectional views taken on the lines 3—3 and 4—4, respectively.

Fig. 5 is a further enlarged front view, partly in section, of the cover lifting means.

Fig. 6 is a similarly enlarged fragmentary sectional view of the cover severing means.

Fig. 7 is a fragmentary plan sectional view taken on line 7—7 of Fig. 4.

Although not shown in the drawings, the pres-

2

ent machine, like the one shown in said pending application, is mounted on wheels or rollers to be mobile for ready movement to a position adjacent to a pile of magazines to be fed to the machine.

5 The machine that is illustrated comprises, generally, a frame 10 that is L-shaped, a conveyor 11 for feeding magazines 12 from a stack 13 thereof, a hopper 14 for holding the magazines in stacked condition, adjustable gate means 15 for gauging the opening through which the magazines are fed, means 16 for lifting the covers of the magazines successively as they are fed by conveyor 11, means 17 for opening the covers outwardly so they lay in a plane substantially parallel to the bodies of the magazines and also serving as hold-down means for said bodies, means 17a for severing the covers from the bodies of the magazines, means 18 for receiving the severed covers, and means 19 for receiving and conveying away the coverless magazines.

The frame 10 comprises a set of front legs 20, a set of back legs 21, a front upper rail 22 connecting the front legs, a back upper rail 23 connecting the back legs, and suitable transverse connecting members 24 connecting the front and back legs. The frame further comprises horizontal members 25 that extend transversely at one end of rails 22 and 23. In the present machine, 25 the conveyor 11 is horizontally disposed but is tilted from the front upwardly and rearwardly to insure a uniform path for the magazines fed thereby. Accordingly, the frame 10 is further provided with a front lower longitudinal member 26 and a rear upper member 27 parallel to rails 22 and 23 for supporting conveyor 11 in said tilted position.

The frame 10, at the rear, is provided with a top plate 28 that extends between rail 23 and member 27 and with a sloping conveyor platen 29 between plate 28 and front rail 22. A somewhat similar platen 30 extends between members 25 for conveyor means 19. Such other members that may be needed to brace the frame members above described may be provided in the usual manner.

45 The conveyor 11 comprises an endless belt 31, the upper run of which rides on platen 29. Pulleys 32 and 33, at opposite ends of the belt are mounted in suitable bearing blocks 34 on members 26 and 27 to hold the belt for movement longitudinally of the upper run in the direction of the arrow 34a (Fig. 1).

50 Drive of the belt is effected by an electric motor 35, through a pulley and belt connection 36 to

a jack shaft 37 and a pulley and belt connection 38 from said jack shaft to roller 32. The high speed of the motor is thereby considerably reduced by the two reduction driving connections 36 and 38 to move the belt at a speed that will feed some ninety magazines per minute.

Magazine-feeding cleats or strips 39 are arranged transversely on the outer face of the belt and these are spaced at a slightly greater distance from each other than the length of the longest magazines to be handled by the machine. Fig. 1 clearly shows this spacing of the cleats. Also, the cleats are made of a thickness to feed the thinness of magazines from stack 13 without encountering the magazine next above in said stack. However, for relatively thick magazines—those approaching the present maximum of one-half inch—each of the cleats may be provided with magazine-pushing clips of suitable height to insure proper feed.

The magazine-receiving hopper 14 is located adjacent the oncoming end of the upper run of belt 31 and need only comprise a front wall 40 and a side wall 41. A back wall 42 is provided only to lend rigidity to the hopper. The magazine stack 13 is placed directly upon belt 31 with the bound backs of the magazines resting against hopper wall 40, the hopper being sloped to accord with the slope of the conveyor. This slope of the conveyor which, in practice, is some 18°, insures that the magazines, as they are fed, retain a position against and in sliding engagement with rail 22.

The wall 41 has its lower edge 43 considerably above the conveyor as best seen in Fig. 3 and it is to this wall that gate means 15 is applied to gauge the space between edge 43 and the conveyor belt. Said means 15 is shown as a plate 44 applied against the outer face of wall 41 and held thereagainst for adjustment in guides 45 by means of a threaded stem 46 connected to said plate, a fixed threaded nut 47 through which the stem extends, and an adjusting handle 48 on said stem. It will be evident that by rotating handle 48, the lower edge of gate plate 44 may be adjusted relative to the upper surface of the conveyor belt to allow only the lowermost magazine of the stack 13 to pass thereby. To insure against mutilation of said lower edge of the gate plate in the event of an improper adjustment, the same may be resilient to yield to a magazine. A rubber strip 49 may be provided to afford such resilience. Thus, for thin magazines, the gate plate may be adjusted quite low—even to be engaged and flexed by the magazines being fed and yet retaining the magazine next above.

The means 16 comprises a free-running suction device 50 and a finger member 51 associated therewith, the former acting to lift the cover 52 of each magazine 12 as the same is fed and the latter holding said cover lifted until the same is engaged by the cover-opening means 17.

The suction device 50 comprises a free-running wheel 53 that has its periphery in gravitational contact with the magazine covers and rolls on its center by virtue of frictional engagement with said covers as the magazines are fed. Said wheel, by means of radial walls 54 is divided into a series of radial ducts 55. The wheel thus provided is mounted for free rotation on a tube 56 which has therein downwardly facing openings 57 and as many progressively smaller openings 58 angularly related thereto as may be required. It will be evident that the duct 55 which is aligned with the larger openings 57 will be subject to

suction to a greater degree than those ducts that are aligned with the smaller openings 58. Thus, as seen in Fig. 5, as a magazine 12 is moved toward the left, and encounters wheel 53, the cover 52, due to the strong suction in that duct 55 which faces directly downward, will be drawn by the suction force against the periphery of the wheel and raised thereby. As the magazine moves to the left, the initially downwardly facing duct will move from register with the large openings 57 to register with the smaller openings 58, thereby reducing the suction force holding the cover against the wheel periphery. This reduction of suction force continues as the magazine moves further to the left and permits the raised portion of the cover to pull away from the wheel as the same continues to turn and the magazine continues its straightline movement toward the left.

By placing the forward edge 59 of finger member 51 below and adjacent the wheel, but slightly above the magazine cover, as said cover is flexed upward as above described, said edge 59 will be introduced between the cover and the body of the magazine to hold the cover raised as the magazine progresses in its feed movement.

The tube 56 extends toward the rear of the machine and is then downwardly curved at 60 to extend through an elongated opening 61 formed in top plate 28. A flexible hose connection 62 extends from tube end 60, and a suction fan 63, driven by an electric motor 64, connects to the opposite end of said hose connection. A pair of trunnions 65 extend from the sides of tube 56 just beyond the bend therein; said trunnions being arranged in notched seats 66 provided in brackets 67 on said top plate 28. Thus the device 50 is freely tiltable on the trunnions so that the wheel 53 thereof falls gravitationally into engagement with the magazines as the latter move by. Since magazines vary in width as well as in length, two or more sets of seats 66 may be provided in said brackets for selectively receiving said trunnions. Thus the wheel 53 can be positioned relative to the bound edges of the magazine, according to the width of the same. The wheel would be placed forward for narrower magazines and rearward for wider ones.

Finger member 51 is connected to device 50 by means of a clamp 68 on the end 69 of tube 56 as shown in Fig. 7. Therefore, once relative adjustment of said finger member and wheel 53 is made, the same need not be disturbed and both together are moved when adjustment of wheel 53 is made.

The means 17 comprises a plate 69 that is hingedly connected to the frame 10 at 70 and is supported by a ledge 71 to be spaced above the upper run of the conveyor belt 31. Said plate is formed with a nose 72 that is immediately adjacent to finger member 51 and which holds the magazine cover 52 raised after the same leaves said finger member. The forward edge 73 of said plate slopes toward the front of the machine toward an upwardly, forwardly and laterally sloping shoe 74 that has the function of engaging the raised magazine cover and turning the same until it lies open in a plane substantially parallel to the body of the magazine, said cover, thereby, projecting forward of the front of the machine as shown best in Fig. 1. It is while the cover 52 is in this condition that the same is severed from the body of the magazine by means 17-a.

Plate 69 also serves as a hold-down for the

magazine while the cover is being severed to prevent any of the pages of said magazine from being lifted while the cover is being opened. Between said plate 69 and gate plate 44 and extending along and rearward of rail 22, there is provided a hold-down plate 75 that is positioned above the bound edges of the magazines to prevent upward displacement while their covers are being lifted, particularly of those magazines that are of light weight.

The cover-severing means 17-a is driven from motor 64 by a belt and pulley drive 76 and comprises a rotary cutter 17 set vertically in a notch provided therefor in the rail 22. The upper portion of the cutter extends above the top edge of the rail and is in a position to slice through the covers of magazines, adjacent their bound edges, as they move beneath plate 69. Fig. 6 best shows this arrangement.

The severed covers are collected in means 18 which comprises a receptacle 78 positioned at the front of the machine immediately beyond the cutter 17. A trough-like member 79, that comprises a false bottom for the receptacle, is provided to make easier and quicker removal of the covers therein, by simply removing the member 79 with the accumulation of covers thereon and replacing the same with an empty member 79, while the machine is in operation.

The means 19 for receiving the coverless magazines comprises the mentioned platen 30 that is positioned beyond and below the top run of feed belt 31, and a conveyor belt 80, the top run of which slides along and is supported by said platen. Said latter belt is driven from jack shaft 37, through bevel gearing 81, a shaft 82, and a belt and pulley drive 83. This drive is relatively slower than that for belt 31 and, as coverless magazines fall from said latter belt onto belt 80, they overlap, one with the other, as seen at the left of Fig. 1, to make it a simple matter to remove a batch of magazines from said conveyor for baling or bundling while the machine is operating.

Should it be desired, for magazines of different sizes, means may be provided for varying the relative speed of conveyor 80, as by introducing change gears between the ends of shaft 82.

The machine above provided needs but one attendant for keeping the stack 13 replenished, removing the accumulations of covers in receptacle 78 and for removing coverless magazines from conveyor belt 80. Although the machine is designed for a large output, a single operator can easily attend the needs of the machine.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described my invention, what I claim and desire to secure by Letters Patent is:

1. A machine for removing the covers of magazines comprising, in combination, a conveyor, a hopper for holding a stack of magazines with the lowermost magazine resting on the conveyor, spaced members on the conveyor for feeding the magazines from the stack, successively, suction means in the path of feed of the magazines and including a free-running wheel in peripheral engagement with the covers of said magazines and

rotated by the covers during movement of the magazines, said suction means lifting the cover of each magazine, a finger member beyond said wheel and positioned in the path of the magazines to extend into the spaces between the bodies of the magazines and the lifted covers thereof to hold said covers raised after release by the suction means, a member in the path of further movement of the magazines for outwardly turning the raised covers, and means in the path of the outwardly turned covers for severing said covers from the bodies of the magazines adjacent the bound edges thereof.

2. A machine for removing the covers of magazines comprising, in combination, a conveyor, a hopper for holding a stack of magazines with the lowermost magazine resting on the conveyor, both the conveyor and the hopper being tipped in a direction transverse to the movement of the conveyor to hold the stack of magazines gravitationally at the low side of the conveyor, spaced members on the conveyor for feeding the magazines from the stack, successively, suction means in the path of feed of the magazines and including a free-running wheel in peripheral engagement with the covers of said magazines and rotated by said covers during movement of the magazines, said suction means lifting the cover of each magazine, a finger member beyond said wheel and positioned in the path of the magazines to extend into the spaces between the bodies of the magazines and the lifted covers thereof to hold said covers raised after release by the suction means, a member in the path of further movement of the magazines for outwardly turning the raised covers, and means in the path of the outwardly turned covers for severing said covers from the bodies of the magazines adjacent the bound edges thereof.

3. A machine for removing the covers of magazines comprising, in combination, a conveyor, a hopper for holding a stack of magazines with the lowermost magazine resting on the conveyor, spaced members on the conveyor for feeding the magazines from the stack, successively, suction means in the path of feed of the magazines and including a free-running wheel in peripheral engagement with the covers of said magazines and rotated by said covers during movement of the magazines, means mounting said suction means for adjustment in a direction transversely of the conveyor, said suction means lifting the cover of each magazine, a finger member beyond said wheel and positioned in the path of the magazines to extend into the spaces between the bodies of the magazines and the lifted covers thereof to hold said covers raised after release by the suction means, a member in the path of further movement of the magazines for outwardly turning the raised covers, and means in the path of the outwardly turned covers for severing said covers from the bodies of the magazines adjacent the bound edges thereof.

4. A machine for removing the covers of magazines comprising, in combination, a conveyor, a hopper for holding a stack of magazines with the lowermost magazine resting on the conveyor, spaced members on the conveyor for feeding the magazines from the stack, successively, suction means in the path of feed of the magazines and including a free-running wheel in peripheral engagement with the covers of said magazines and rotated by said covers during movement of the magazines, said suction means lifting the cover of each magazine, a finger member beyond said

wheel and positioned in the path of movement of the magazines to extend into the spaces between the bodies of the magazines and the lifted covers thereof to hold said covers raised after release by the suction means, said suction means and finger member being fixedly connected to each other, means mounting the suction means and finger member for adjustment in a direction transversely of the conveyor, a member in the path of further movement of the magazines for outwardly turning the raised covers, and means in the path of the outwardly turned covers for severing said covers from the bodies of the magazines adjacent the bound edges thereof.

5. A machine for removing the covers of magazines comprising, in combination, a conveyor, a hopper for holding a stack of magazines with the lowermost magazine resting on the conveyor, spaced members on the conveyor for feeding the magazines from the stack, successively, suction means in the path of feed of the magazines and including a free-running wheel in peripheral engagement with the covers of said magazines and rotated by the covers during movement of the magazines, said suction means lifting the cover of each magazine, a finger member beyond said wheel and positioned in the path of the magazines to extend into the spaces between the bodies of the magazines and the lifted covers thereof to hold said covers raised after release by the suction means, a member in the path of further movement of the magazines for outwardly turning the raised covers, said member comprising a plate spaced above and transversely coextensive with the conveyor and beneath which the bodies of the magazines move, said plate having a nose that enters into the space between the body of each magazine and the raised cover thereof to hold said cover raised after the same leaves the finger member, said plate being provided with an upwardly angularly directed shoe part that outwardly turns the cover held raised by said nose, and means in the path of the outwardly turned covers for severing said covers from the bodies of the magazines adjacent the bound edges thereof.

6. A machine for removing the covers of magazines comprising, in combination, a conveyor, a hopper for holding a stack of magazines with the lowermost magazine resting on the conveyor, spaced members on the conveyor for feeding the magazines from the stack, successively, suction means in the path of feed of the magazines and including a free-running wheel in peripheral engagement with the covers of said magazines and rotated by the covers during movement of the magazines, said suction means lifting the cover of each magazine, a finger member beyond said wheel and positioned in the path of the magazines to extend into the spaces between the bodies of the magazines and the lifted covers thereof to hold said covers raised after release by the suction means, a member in the path of further movement of the magazines for outwardly turning the raised covers, means in the path of the outwardly turned covers for severing said covers from the bodies of the magazines adjacent the bound edges thereof, a receptacle be-

yond and beneath the severing means for collecting the severed covers, and a conveyor beyond the discharge end of and below the magazine-feeding conveyor for receiving the coverless magazines.

7. A machine for removing the covers of magazines comprising, in combination, a conveyor, a hopper for holding a stack of magazines with the lowermost magazine resting on the conveyor, spaced members on the conveyor for feeding the magazines from the stack, successively, suction means in the path of feed of the magazines and including a free-running wheel in peripheral engagement with the covers of said magazines and rotated by said covers during movement of the magazines, said suction means lifting the cover of each magazine, a finger member beyond said wheel and positioned in the path of the magazines to extend into the spaces between the bodies of the magazines and the lifted covers thereof to hold said covers raised after release by the suction means, a member in the path of further movement of the magazines for outwardly turning the raised covers, means in the path of the outwardly turned covers for severing said covers from the bodies of the magazines adjacent the bound edges thereof, a receptacle beyond and beneath the severing means for collecting the severed covers, a conveyor beyond the discharge end of and below the magazine-feeding conveyor for receiving the coverless magazines, and means for driving the magazine-receiving conveyor at a slower rate than the feeding conveyor, whereby the coverless magazines fall thereon in overlapping relation to each other.

8. A machine of the character described, comprising a cutter, means arranged to move a series of bound books one after the other in a direction toward and beyond said cutter, means in the path of movement of the books and in advance of the cutter to raise one outer sheet of each book as the same moves therewith and to dispose said sheet in a position to be severed from the body by said cutter when the book moves past the latter, collecting means beyond the cutter to receive the books from which an outer sheet has been severed, and collecting means disposed laterally of said path of movement and between the cutter and the book-collecting means to receive the severed sheets.
